BANK PROTECTOR

Angelo R. Freda, Orange, N. J.

Application May 29, 1930. Serial No. 457,372

1 Claim. (Cl. 268—2)

This invention relates to bank protective devices and has special reference to a protective screen for tellers, cashiers and other persons receiving and paying money to the public through a window or the like.

One important object of the invention is to provide an improved guard arranged so that it constantly tends to position across a money window but which is normally held out of position by a latch.

A second important object of the invention is to provide improved means for quickly positioning a screen of this kind across a window.

A third important object of the invention is to provide improved means for restoring the screen to inactive or housed position after use.

A fourth important object of the invention is to provide improved means for latching the screen from movement.

With the above and other objects in view, the invention consists in general of certain novel details of construction and combinations of parts hereinafter more fully described, illustrated in the accompanying drawings and claimed.

In the accompanying drawings like characters of reference indicate like parts in the several views, and—

Figure 1 is an elevation of a portion of a money cage showing the screen in inactive or housed position;

Figure 2 is a similar view with the screen elevated;

Figure 3 is an enlarged section on the line 3—3 of Figure 1;

Figure 4 is an enlarged section on the line 4—4 of Figure 1;

Figure 5 is an enlarged section on the line 5—5 of Figure 1;

Figure 6 is a section on the line 6—6 of Figure 3; and

Figure 7 is an enlarged section on the line 7—7 of Figure 2.

In the embodiment of the invention here illustrated, there is shown a partition 10 above which is a window 11. A shaft or counter 12 forms the bottom of this window and extends rearwardly therefrom into the money cage, the general public transacting business through the window 11 from in front of the partition. This

counter is provided with a slot 13 extending between the sides of the window frame and slideable vertically through this slot is a screen plate 14 provided with a frame having a top plate 15 which, when the screen is lowered, closes the slot 13 so that money is prevented from dropping

therethrough or lodging therein. This plate is of bullet proof material.

Weight boxes 16 are arranged at opposite sides of the window frame and are provided at their upper ends with slots 17 and pulleys 18 similar to the slots and pulleys of ordinary window sash. Steel cables 19 run over these pulleys and each cable has one end attached to the frame of the plate 14 and carries at its other end a heavy weight 20 arranged to drop in the weight box 60 and be checked by a spring 21. Positioned to the rear of the partition 10 are bearings 22 wherein is journalled a rock shaft 23 having rock arms 24 extending upwardly therefrom. In front of these rock arms are guide brackets 25 where- 65 through slide latches 26 having their rear ends pivotally connected to the upper ends of the rock arms 24 and their forward ends normally engaging in openings 27 formed adjacent the bottom of the plate 14. A further rock arm 28 extends up from the shaft 23 and has the rear 70 end of a tension spring 29 secured thereto. A post 30 is fixed to the floor forwardly of the rock arm 28 and the remaining end of the spring 29 is attached thereto, the latches thus being 75 constantly urged into plate engaging positions. Rock arms 31 extend rearwardly from the shaft 23 and carry a pedal bar positioned conveniently to the foot of the employee behind the window. By pressing this bar downwardly the latches are 80 drawn back and the guard plate released to fly 85 up and close the window.

Extending between the lower ends of the boxes 16 is a resetting shaft 32 on which are wound cords or cables 33 having their free ends attached 90 to the bottom of the plate 14. A cable 34 is wound at one end in the opposite direction on the shaft 32 and has its other end wound on a shaft 35 supported in a frame 36. The shaft 35 carries a belt pulley 37 which is connected by a belt 38 95 with a belt pulley 39 fixed on a shaft 40 supported in the frame 36. On the shaft 40 is wound a cable 41 supporting a counter weight 42. A crank 43 is used to actuate the shaft 35 for resetting the guard plate.

A belt tightener 45 may be used to keep the belt 38 tight and the plate 14 may be provided with peep or sight holes 45 normally covered by swinging shutters 46.

In operation, when danger occurs the employee 105 simply presses on the bar 32 and releases the latches. The weights 20 will drop and the guard plate fly up. At the same time the cables 33 will unwind and the cable 34 wind onto the shaft 32 and off the shaft 35. This will effect winding of 110

the cable 41 on the shaft 40 and will lift the weight 42. After the danger is passed the crank 43 is rotated to wind the cable 34 on the shaft 35 and thus effect drawing down of the guard 5 plate.

There has thus been provided a simple and efficient device of the kind described and for the purpose specified.

It is obvious that changes may be made in the 10 form and construction of the invention without departing from the principles thereof. It is not, therefore, desired to confine the invention to the exact form herein shown and described but it is desired to include all such as come within the 15 scope claimed.

Having thus described the invention, what is claimed is:

Operating means for a protective device for
